UNITED STATES PATENT OFFICE.

BENJAMIN F. ERWIN, OF FAIRFAX, MISSOURI.

END-GATE.

1,271,024.

Specification of Letters Patent.

Patented July 2, 1918.

Application filed May 16, 1916. Serial No. 97,861.

To all whom it may concern:

Be it known that I, BENJAMIN F. ERWIN, a citizen of the United States, residing at Fairfax, in the county of Atchison and State 5 of Missouri, have invented certain new and useful Improvements in End-Gates, of which the following is a specification.

This invention relates to certain new and useful improvements in end gates and it 10 contemplates, primarily, the provision of a novel end gate and means for securing the same in a closed position and also in a partly open and approximately vertical position thus assisting the operator to properly dispense the contents of the wagon body and to 15 thus effectually control the delivery of the contents.

A still further object of the invention is to provide a device of the type in question 20 that is extremely simple in construction, strong and durable, and highly practical from both the standpoint of the manufacturer and the standpoint of the user; and which, it is believed, may be manufactured 25 at a comparatively low cost.

Various other objects and advantages will become apparent during the continuance of the following description.

These objects are accomplished by such 30 means as are shown in their preferred form in the accompanying drawings, described in the following specification, and then more specifically pointed out in the appended claims.

35 In the accompanying drawings, wherein like characters designate like parts throughout the several views:

Figure 1 is a view in side elevation showing a portion of a wagon body, and my improved end gate as in a closed position;

Fig. 2 is a view similar to Fig. 1 showing the gate in a partly open position;

Fig. 3 is a view in section taken on line 3-3 of Fig. 1;

45 Fig. 4 is a fragmentary view of the end of the wagon box or body showing the end gate in cross section and in a closed position; and

Fig. 5 is a view in detail illustrating, more 50 clearly, the locking means for the end gate.

In the drawings; 10 designates the wagon box or body in connection with which my improved end gate is shown, but it is to be understood, of course, that I am not limited 55 to the specific application of the end gate and that the latter may be also used in con-

nection with wagon bodies of other types and constructions, if it is so desired.

In reducing my invention to practice, I provide the wagon box 10, adjacent its rear 60 end and its upper edge, with suitably spaced strap bearings 11 which are secured in place as at 12, and carry slightly offset guide brackets 13, as clearly shown in Fig. 3. These bearings are positioned on each side of 65 the wagon box and are designed to be engaged by certain means carried by the end gate, as will subsequently appear. It will also be noted that the forward one of the brackets 13 has positioned therethrough, an 70 inwardly directed stud 14, the purpose of which will be presently set forth.

I further provide the wagon box 10 with spaced bearings 15, these bearings being positioned adjacent the rear end and the lower 75 edge of the box, secured in place as at 16, and having portions 17 extending beneath the wagon box, as illustrated in Fig. 3. The bearings 15 also carry offset brackets 18 (as shown in Fig. 3), the forward one of which 80 carries a securing pin, or stud, 19, similar to the stud 14, above described.

The end gate 20, shown in the present embodiment, carries upon its outer face, spaced sills 21 and 22, respectively, sill 21 carrying forwardly directed arms 23, as at 24, while arms 25 which are of greater length than arms 23 are pivotally mounted on the end gate 20 adjacent the sill 22, as at 26. Arms 23 pass between brackets 13 and bearings 11, and rest upon studs 14, while arms 25 pass between brackets 18 and bearings 15, and rest upon studs 19. All of the arms carry depending catches or shoulders 27 and 28. The catches or shoulders 28 engage 95 respectively with the studs 14 and 19 when the end gate is in the position shown in Fig. 2, and the catches 27 engage respectively with the studs 14 and 19 when the end gate is in a closed position, Fig. 1. This construction is illustrated to advantage in Fig. 5.

In order to enable the operator to lock the arms 23 and 25 securely in adjusted position, I provide the forward ones of the brackets 13 and 18 with pivoted cams 29 which have 105 handles 30 whereby they may be operated. By positioning the cams, as illustrated in Fig. 5, the arms will be held in secure engagement with the respective studs, and as a consequence, the end gate will be locked in 110 its respective position. On the other hand, by releasing the arms from action of the

cams the end gate may be quickly and easily shifted either to a closed or open position, and subsequently locked by the operator. In its open position, the end gate stands in an approximately vertical position and in spaced relation to the open end of the wagon body or bed, as shown in Fig. 2. It will be seen, therefore, that the end gate, when in open position, directs the material downward and prevents it from moving rearward beyond the limit determined by the position of the end gate. As an example of the operation and effect of this end gate, let it be assumed that the wagon body is loaded with coal which it is desired to dump into a trap door or man-hole at the edge of a sidewalk: the fastening device 30 will be released and the weight of the coal will force the end gate into the spaced relation shown in Fig. 2 and the coal is at once allowed to pass downward through the downwardly diverging space between the wagon body and end gate, the latter preventing the coal from shooting over and beyond the trap door or man-hole. When the rear end of the wagon body has been emptied and there remains a quantity of coal in the front end of the wagon body, a scoop may be used in the ordinary way for passing the coal to the rear end of the wagon body, and this may be done without the possibility of passing the coal beyond the pre-determined limit of the end gate. Because of the inclined open position of the end gate, the space through which the material passes is wider at the bottom than at the top, thereby preventing the commodity from banking or choking in its delivery.

From the foregoing, it is believed that the advantages and novel features of my invention will be clearly understood, and therefore further detailed description is deemed unnecessary.

In reducing the invention to practice, it will be found that the form referred to herein as the most practical and preferred embodiment is the most efficient, but realizing that certain conditions will necessarily vary in accordance with the adoption of the device, it is emphasized that various minor changes in the details of construction and in

the proportion of parts may be resorted to when required without sacrificing any of the advantages of the invention, as defined in the appended claims.

Having thus fully described the invention, 55 what is claimed to be new and desired to be secured by Letters Patent, is—

1. In combination with a wagon body and an end gate therefor, upper and lower arms pivoted to the end gate near the top and the bottom thereof, respectively, and extending along the sides of the wagon body and having depending catches in their rear ends, upper and lower bearings at the sides of the wagon body to receive the respective arms, 60 means co-acting with the said catches and constituting stops to hold the end gate in both closed and open position, and cams on the wagon body to hold the catches in the path of the said stops. 70

2. The combination of a wagon body, an end gate therefor, lower supporting members pivotally connected to the lower portion of the end gate, upper supporting members pivotally connected to the upper portion of the 75 end gate, lower guiding members on the wagon body and carrying said lower supporting members and allowing the latter to move horizontally with relation thereto, upper guiding members carrying said upper 80 supporting members and allowing the latter to move horizontally with relation thereto, and securing devices co-operative with said lower supporting members and upper supporting members for holding said end gate 85 in its closed position and allowing it to move into such position as to provide a downwardly diverging outlet opening, the construction of said upper and lower supporting members being such as to allow a 90 greater movement of the lower end of said end gate than of its upper end and to arrest said end gate's movement away from the wagon body.

In testimony whereof I affix my signature 95 in presence of two witnesses.

BENJAMIN F. ERWIN.
